UNITED STATES PATENT OFFICE.

ARCHIA L. ROSS, OF NEW YORK, N. Y., ASSIGNOR OF ONE-HALF TO DAVID HYAMS, OF SAME PLACE.

BAG-CLOSURE.

SPECIFICATION forming part of Letters Patent No. 605,343, dated June 7, 1898.

Application filed June 25, 1897. Serial No. 642,256. (No model.)

To all whom it may concern:

Be it known that I, ARCHIA L. ROSS, of New York city, in the county and State of New York, have invented certain new and useful 5 Improvements in Bag-Closures, of which the following is a full, clear, and exact description.

The invention relates to bags used for receiving ashes, papers, and other refuse from 10 households and the like; and its object is to provide certain new and useful improvements in bag-closures whereby a bag can be conveniently suspended and its mouth held open to allow of filling the bag with refuse material 15 and when the bag is full to permit of closing the mouth of the bag hermetically to prevent spilling or escape of the contents when transporting the bag from one place to another.

The invention consists of certain parts and 20 details and combinations of the same, as will be fully described hereinafter and then pointed out in the claims.

Reference is to be had to the accompanying drawings, forming a part of this specification, 25 in which similar characters of reference indicate corresponding parts in all the figures.

Figure 1 is a perspective view of the improvement as suspended and with the mouth of the bag open to receive the refuse material. 30 Fig. 2 is a plan view of the improvement with the mouth open and part broken out. Fig. 3 is an enlarged sectional side elevation of the improvement with the mouth open. Fig. 4 is a similar view of the same with the frame 35 closed, and Fig. 5 is a side elevation of a modified form of keeper.

The bag A is made of canvas or other suitable fabric material and is provided at its mouth with a frame B, preferably made of spring-wire 40 and formed with two members B' B², arched or U shape and pivotally connected with each other at their ends at B³ to form a hinge-joint to swing the members toward each other to close the mouth of the bag or from each other 45 to open the bag, as indicated in Figs. 1, 2, and 3.

The member B² is formed at or near its middle with a catch B⁴ by doubling a portion of the member and bending the doubled-up 50 portion transversely and forming the doubled-up portion with a shoulder B⁵, adapted

to snap under the middle part of the member B', so as to lock the two members of the frame together. (See Fig. 4.)

On the member B', and preferably at the 55 middle thereof, is hung a U-shaped holder or loop C, serving a twofold purpose—namely, of suspending the bag from a hook, nail, or like device D, as illustrated in Fig. 1, and to enable the operator to conveniently open the 60 bag by the operator taking hold of the said loop C with one hand and pulling on the free end of the catch B⁴ in a downward direction to unlock the shoulder B⁵ from the member B'.

In order to hermetically seal the mouth of 65 the bag when the frame B is closed, I provide a packing-strip E, preferably made of braid, cord, or like material and sewed to the hem of the bag, engaging the members B' B² of the frame B, the said packing following the lines 70 of the frame members, so that when the latter are closed the opposite sides of the packing abut one upon the other, as plainly indicated in Fig. 4, to hermetically seal the mouth of the bag.

Now by the arrangement described the bag can be readily opened at its mouth and one member of the frame is readily suspended from a nail, hook, or like support, so as to keep the bag open to permit of conveniently 80 filling ashes, paper, or other refuse into the said bag. When the bag is full, then it is taken off the hook and its mouth closed while locking the frame members together, as previously explained. In closing the mouth of 85 the bag the same is hermetically sealed, as above mentioned, to allow of conveniently transporting the bag from one place to another without danger of spilling the contents thereof. 90

For very large bags any desired number of catches B⁴ may be used on a single member B², if desired—preferably, however, one on each side of the loop C. In order to prevent the members B' and B² from shifting one on 95 the other when closed, I may form the member B' with a U-shaped keeper or receiver B⁶ for the catch B⁴ to snap under, as shown in Fig. 5.

Having thus fully described my invention, 100 I claim as new and desire to secure by Letters Patent—

1. A bag-closure, comprising a frame having two members pivotally connected with each other, and each formed of spring metal, one member being provided at or near its middle with a pivoted loop, and the other with a transversely-extending catch having a shoulder adapted to snap under the other frame member, between the members of the said loop to lock the members and keep the frame in a closed position, and a cord packing arranged on the inside of the frame and following the line of the members thereof, so that when the bag is closed, the said packing hermetically seals the mouth of the bag, substantially as shown and described.
- 15 2. A bag-closure, comprising a frame having two members pivotally connected with each other, and each formed of spring metal,

one member being provided at or near its middle with a **U**-shaped keeper and the other with a transversely-extending catch formed by doubling a portion of the member, then bending the doubled-up portion and forming the same with a shoulder adapted to snap under the keeper of the other frame member, to lock the member and keep the frame in a closed position, a loop pivoted on the other frame member for suspending the bag and for conveniently opening the frame members and a cord packing on the inside of the frame and following the line of the members thereof, substantially as shown and described.

ARCHIA L. ROSS.
